UNITED STATES PATENT OFFICE

EDMUND C. MOGFORD AND GEORGE SPATTA, OF BUCHANAN, MICHIGAN, ASSIGNORS TO CLARK EQUIPMENT COMPANY, OF BUCHANAN, MICHIGAN, A CORPORATION OF MICHIGAN

SPRING PAD

Application filed September 17, 1930. Serial No. 482,401.

This invention relates to spring pads for tubular front axles.

In automotive vehicles, the front axles are frequently composed of a tubular member 5 consisting of thin walled tubing which is formed and forged to the required shape. These axles, while advantageous for the reason that they are considerably lighter than a solid axle of equal strength, have heretofore 10 been handicapped by the lack of an inexpensive yet entirely satisfactory spring pad for attaching the spring to the axle, the use of a clamping and encircling member or members being undesirable because of the 15 added weight.

In the past it has been the usual practice to forge or press a spring pad of suitable size and shape and to attach it to the tubular axle by welding. This method is frequently 20 disadvantageous for the reason that the welds by which the pad is attached to the axle weakens the tensile strength of the axle and thereby renders it more subject to bending due to stresses set up in it when the 25 wheels of the vehicle strike an uneven spot in the road and also when the springs rebound after the wheels have passed such an obstacle. Furthermore, a spring pad of this type imposes tensile stress upon the welds 30 by which the pad is attached to the axle and if these welds are not properly made there is great likelihood of the spring pad being torn loose from the axle by relatively small stresses and if the welds are properly 35 made there still remains a possibility of the spring pad being torn loose by shocks and torques placed upon the axle, particularly if these shocks tend to rotate the axle and at the same time to lift the springs and pad 40 from it. Under these conditions the edge of the welds is placed under excessive tension and the pad may be peeled or torn from the axle.

In our present invention, we have provided a new and improved spring pad con-

sisting of a forged pad attached to a tubular front axle by means of a forged band encircling the axle and riveted to the spring pad itself, this band taking all of the tensile stresses which tend to separate the pad from the axle. The edges of the spring pad are also welded to the axle member, these welds being called upon to resist only the stresses tending to turn the spring pad upon the axle, and consequently they do not need to be as large as the welds used heretofore and they may therefore be made without materially weakening the axle itself.

Now to acquaint those skilled in the art with the teachings of our invention reference is made to the accompanying drawing in which a preferred embodiment of it is shown by way of example and in which:

Figure 1 is a plan view of a spring pad attached to an axle,

Figure 2 is an elevational view of the pad shown in Figure 1, and

Figure 3 is a cross-sectional view taken substantially along the line 3—3 of Figure 2 looking in the direction of the arrows and with a spring in place on the pad.

Referring to the drawing now in more detail, a section of thin wall tubular front axle is indicated at 1, and a spring pad 2 is shown attached thereto in accordance with the teachings of our invention.

The spring pad 2 preferably consists of a metallic forging having a flat upper face 3 containing recesses or depressions 4 and 5 and a plurality of holes 6, 7, 8, 9, 10, 11 and 12 all of which are disposed with their axes normal to the plane of the face 3 of the spring pad. A similarly shaped punching may of course be substituted within the teachings of our invention. The central hole 9 provides a clearance into which the screw bolt of a spring assembly can project, this screw bolt assisting in properly centering the spring upon the spring pad.

The recesses 4 and 5 afford a cavity into

which the ends of the U-strap 14 extend when projected through the holes 11 and 7 in the spring pad 2. The end 13 of this strap is riveted over at 15 to securely fasten 5 the spring pad and strap together. The opposite end 16 of the strap 14 is projected through the hole 7 in the spring seat and projected into the recess 5 where it is riveted as at 17 to securely attach the other end of 10 the strap 14 to the spring pad. Preferably the holes 7 and 11 are tapered as shown at 18 and 19 in Figure 3 so that the riveting of the ends of the strap 14 forces that strap out into the taper to thereby securely bind it 15 to the spring pad. By this arrangement, the spring pad is securely attached to the tubular axle 1 without welding and the forged strap 14 by which it is attached is thereby enabled to take up stresses which 20 tend to separate the pad from the axle.

The lower face of the pad 2 contains an arcuate seat 30 shaped to conform to the perimeter of the axle 1, and bosses 31 and 32 which surround holes 7 and 11 respectively. The inner ends of these bosses are likewise shaped as shown at 33 and 34, to conform to the contour of the axle 1. Obviously if the axle 1 is not round, surfaces 30, 33 and 34 are changed accordingly so 25 that they remain capable of firmly seating the pad on the axle.

In order to prevent rotation of the spring pad 2 and strap 14 around the axle 1 responsive to torques set up by the application 30 of the brakes and other similar forces, the spring pad 2 is welded at 20 and 21 to the axle 1, these welds being called upon to resist only the relatively small torques tending to rotate the two members with respect 35 to each other. Because the torques that the welds are called upon to resist are relatively small, the welds are themselves small and can be made without injuring the walls of the tubular axle.

40 The spring assembly indicated generally at 22 in Figure 3 rests upon the flat upper face 3 of the spring pad with its screw bolt 23 projecting into the central opening 9 in the spring pad. The springs are attached 45 to the pad in any preferred manner such as by the bolts 24 which project through holes 6, 8, 10 and 12 in the spring pad and through cross links 25 located above the spring 22. Nuts 26 threaded on the ends of 50 the bolts and against the upper surface of the cross links 25 serve to securely bind the spring 22 to the spring pad 2 and consequently to the axle 1.

The machine bolts 24 and nuts 26 and 55 plates 25 shown in Figure 3 are shown by way of example only as any other preferred attaching device may be employed to attach the spring to the spring pad within the teachings of our invention. For example a forged U-shackle may be substituted 60

for the bolts shown, this U-shackle being placed with its closed end over the upper surface of the spring and with its nuts disposed beneath the spring pad in the positions occupied by the bolt heads 27 shown in the 70 drawing.

By this arrangement, the spring pad is securely mounted on the axle and held thereon by forgings which are of sufficient strength to resist the stresses placed upon them during the operation of the vehicle. Any tendency of the spring pad to turn on the axle is resisted by small welds and as a result the attachment of the spring pad to the axle in no way weakens the tensile 80 strength of the axle. The arrangement of the forged spring pad and strap shown in the drawing is relatively inexpensive and also results in a material decrease in the weight of the spring pad, since the employment of large heavy U-bolts completely encircling the axle and springs is eliminated. 85

While we have chosen to show our invention by illustrating a preferred embodiment of it, we have done so by way of example 90 only as there are many modifications and adaptations which can be made by one skilled in the art within the teachings of our invention.

Having thus complied with the statutes 95 and shown and described a preferred embodiment of our invention, what we consider new and desire to have protected by Letters Patent is pointed out in the appended claims. 100

What is claimed is:

1. A spring pad comprising a unitary saddle member having a plurality of holes through it, a seat shaped to conform to the contour of the axle on which the saddle-member is to be placed, a flat seat on which the spring rests, and a U band encircling the axle and projecting through certain ones of said holes and riveted adjacent said flat seat to hold the pad on the axle. 110

2. A spring pad for tubular axles comprising a forging having a plurality of holes, a seat conforming to the contour of the axle, a flat seat on which the spring rests, counterbores in said flat seat, a band encircling the axle and projecting through certain of said holes into said counterbores where they are riveted to hold the pad on the axle against stress tending to separate them, and ears projecting beyond said axle, said ears containing others of said holes through which bolts are passed to attach the spring to the pad to thereby mount it on the axle. 115

3. In combination with an axle of circular section, a spring pad having a seat portion resting on the axle, said pad having holes on opposite sides of said seat, and a U-shaped clip having a thin strap portion at its middle and rod-like shanks at its ends, 120

said clip engaging the axle and the shanks extending through the holes, said holes being enlarged at their upper ends, the upper ends of the shanks having holding means disposed in said recesses, there being welds between the pad and the axle to resist torsional stresses between them.

In witness whereof, we hereunto subscribe our names this 13th day of September, 1930.

EDMUND C. MOGFORD.

CERTIFICATE OF CORRECTION.

Patent No. 1,908,856.

May 16, 1933.

EDMUND C. MOGFORD, ET AL.

It is hereby certified that error appears in the printed specification of the above numbered patent requiring correction as follows: Page 2, line 112, claim 2, for "forging" read "saddle member"; and that the said Letters Patent should be read with this correction therein that the same may conform to the record of the case in the Patent Office.

Signed and sealed this 1st day of August, A. D. 1933.

M. J. Moore.

(Seal)

Acting Commissioner of Patents.
